CLARENCE NOEL ISAACS, OF NEWARK, NEW JERSEY.

TIMER.

No. 897,743.

Specification of Letters Patent.

Patented Sept. 1, 1908.

Application filed December 13, 1907. Serial No. 406,276.

To all whom it may concern:

Be it known that I, CLARENCE NOEL ISAACS, a subject of the King of Great Britain, and a resident of Newark, in the county 5 of Essex and State of New Jersey, have invented a new and Improved Timer, of which the following is a full, clear, and exact description.

This invention relates to certain improvements in timers adapted for use in connection with internal combustion engines, for closing the circuit through the igniter to produce the explosion, and the object of the invention is to so construct the timer that the 10 circuit will be closed a substantially uniform length of time for each explosion, irrespective of the speed at which the engine may be running.

The movable terminal which is intermittently brought into engagement with the other terminal to close the circuit, preferably is provided with lost motion connections and engages with a stop just prior to its engagement with the stationary terminal. The 15 movable terminal or contact arm is thus momentarily stopped, and when it does pass the obstruction, it contacts with and passes the terminal closely adjacent thereto under the influence of a spring, the tension of which is not in any way dependent upon the speed at 20 which the shaft bearing the contact arm is rotated.

Reference is to be had to the accompanying drawings, forming a part of this specification, in which similar characters of reference indicate corresponding parts in all the figures, and in which

Figure 1 is a central longitudinal section through a timer constructed in accordance 40 with my invention, said section being taken on the line 1—1 of Fig. 2; Fig. 2 is an end view of the operating parts of the timer, the inclosing casing being cut on the line 2—2 of Fig. 1; and Fig. 3 is an end view of one of the 45 stationary terminals or brushes.

The essential features of my timer include a pivoted contact arm, the terminal portion of which is secured to the rotating shaft by lost motion connections, a stationary terminal, and an obstruction adjacent thereto, serving 50 to retard the contact arm.

In the specific embodiment of my invention which I illustrate in the accompanying drawings, I employ a rotating shaft 10, adapted to be continuously rotated from the crank shaft of the engine, and mounted on

the shaft adjacent the end thereof is a suitable casing, 11, having peripheral walls 12 and a removable end plate or cover 13. The shaft continuously rotates while the casing 60 remains substantially stationary, although rotatable through a portion of a revolution to advance or retard the time of circuit-closing contact between the terminals, as is common in the art. The circumferential wall 12 65 of the casing carries a plurality of brushes or stationary terminals, and an obstruction adjacent each of these terminals, while the shaft bears a contact arm rotatable to engage with the several terminals in succession. The 70 stationary terminals are insulated from the casing wall, that is, if the latter is made of conducting material as in the present instance, and it is connected to a wire at its outer end, leading to the igniter or spark coil, 75 according to the nature of the ignition system. Each terminal preferably includes a radially-disposed bolt 14, extending through the casing wall and insulated therefrom by a jacket 15^a and supporting at its inner end 80 two oppositely disposed brushes 16, between which the end of the contact arm passes, the brushes being spaced apart by a portion 15 of the bolts 14. The inner end of the bolt is preferably rectangular in cross section, and 85 the two brushes are preferably L-shaped. The two brushes are rigidly secured to opposite sides of the rectangular end of the bolt, and are provided with portions 17 extending substantially circumferentially of the casing 90 or along the path taken by the end of the contact arm. Each brush along the length of its terminal portion 17, is bent inwardly to reduce the distance between the two, and then bent outwardly again, as clearly illustrated in Fig. 3. The outer end of each bolt 95 constitutes a binding post, to which the wires 18 are connected. Adjacent each terminal or pair of brushes, is an obstruction 19, preferably supported by the bottom wall of the casing and extending to a point adjacent the several terminals.

The rotatable shaft 10 carries an arm formed of two sections, one section 20 keyed or otherwise rigidly secured to the shaft and 105 the other section 21 pivoted adjacent the outer end of the section 20. The section 20 carries a laterally extending shoulder or projection 22, and the section 21 carries a shoulder or projection 23, normally extending substantially parallel to the projection 22. The 110 terminal portions of these projections are

connected by a coil spring 24, normally tending to draw them toward each other and to hold the arm sections 20 and 21 in substantially the same straight line. The section 20 5 preferably carries a stop 25 with which the section 21 engages to limit the movement caused by said spring. The end of the arm section 21 is adapted to engage with the several obstructions 19, and is somewhat thinner 10 than the heads of the several bolts 14, whereby it may pass between the brushes without contacting therewith, save at their inwardly bent portions.

In the operation of my improved device, 15 one wire from the battery or other source of electrical energy, is connected to the engine frame, whereby the current may pass through the shaft 10 to the end of the contact arm, while the igniters of the several engine cylinders are connected to the wires 18. As the 20 shaft 10 rotates, the contact arm section 21 engages with the obstruction 19 and is retarded, while the other arm section 20 continues uninterrupted. The spring 24 is expanded until the end of the arm section 21 is bent backward so that it can pass the end of 25 the obstruction 19. The instant it reaches the position 21^a shown in dotted lines in Fig. 2, the spring instantly pulls the arm section 21 through between the brushes, so that it makes and breaks circuit therewith for a very brief interval. The forward motion of the arm section is due almost entirely to the spring, so that the speed of rotation of the 30 shaft 10 has very little, if any, bearing upon the length of time the contact arm is in engagement with the stationary terminals. Thus, the same amount of current is used and the spark passes for the same length of time, 35 whether the engine be running at low speed or at high speed, and, furthermore, it is impossible for the terminals to be in contact with each other as the engine stops.

In the constructions commonly employed, 40 if the circuit be closed a sufficient time to produce the desired spark and secure the ignition at high speed, then the batteries are wasted and the current passed for an unnecessary length of time at low speed. Furthermore, in the ordinary construction, 45 should the engine stop in one portion of the revolution, the circuit will be closed continuously and the batteries exhausted, while the engine is standing still. These difficulties 50 are entirely overcome by means of my invention.

Having thus described my invention, I claim as new and desire to secure by Letters Patent:

60 1. In a circuit closer, a terminal, a pivoted

arm adapted to intermittently engage therewith to close an electric circuit, and an obstruction adjacent said terminal and adapted to engage with said arm prior to the engagement of the latter with said terminal. 65

2. In a circuit closer, a rotatable shaft, an arm secured thereto and including lost motion connections, a spring for holding said arm in one of its limiting positions, a terminal adapted to be engaged by said arm to close 70 an electric circuit, and an obstruction in the path of said arm adjacent said terminal.

3. In a circuit closer, a terminal, a rotatable shaft, an arm carried by said shaft and including two sections pivoted together, a 75 spring for holding said sections in a predetermined position in respect to each other, and an obstruction adjacent said terminal and in the path of said arm, whereby the end of said arm is retarded and the time of engagement between said arm and said terminal rendered substantially uniform independently of the speed of rotation of the shaft. 80

4. In a circuit closer, a rotatable shaft, an arm carried thereby, a terminal including 85 two brushes spaced apart and adapted to engage with the end of said arm as the latter passes therebetween, means for retarding said arm prior to its engagement with the brushes, and a coil spring for moving said 90 arm between said brushes independently of the speed of rotation of the shaft.

5. In a circuit closer, the combination of a substantially stationary casing, a rotatable shaft extending into said casing, an arm carried by said shaft, said arm being formed of two sections, one of which is rigidly secured to said shaft and the other of which is pivoted to the first-mentioned section and movable in respect thereto, a spring for holding said 100 sections in one of their two limiting positions in respect to each other, a terminal carried by said casing and lying in the path of said second-mentioned arm section, and an obstruction carried by said casing adjacent said terminal and adapted to engage with said arm prior to the engagement of the latter with said terminal, whereby the end of said arm is retarded and the time of engagement with 105 said arm and said terminal rendered substantially uniform independently of the speed of rotation of the shaft. 110

In testimony whereof I have signed my name to this specification in the presence of two subscribing witnesses.

CLARENCE NOEL ISAACS.
